(57) **CLAIM**

We claim the ornamental design for a wearable mobile accessory, as shown and described.

DESCRIPTION

FIG. 1 is a top, left, front perspective view of a wearable mobile accessory showing my new design, shown in a closed position;

FIG. 2 is a front elevational view thereof, the rear elevational view being a mirror image thereof;

FIG. 3 is a left side elevational view thereof;

FIG. 4 is a right side elevational view thereof;

FIG. 5 is a top plan view thereof;

FIG. 6 is a bottom plan view thereof;

FIG. 7 is a top, left, front perspective view of a wearable mobile accessory, shown in an open position;

FIG. 8 is a top, right, front perspective view thereof;

FIG. 9 is a front elevational view thereof;

FIG. 10 is a left side elevational view thereof;

FIG. 11 is a right side elevational view thereof

FIG. 12 is a top plan view thereof; and,

FIG. 13 is a bottom plan view thereof.

The broken lines in the drawings are for the purpose of illustrating unclaimed portions of the wearable mobile accessory and form no part of the claimed design.
